(57) **CLAIM**

The ornamental design for a main body for indoor plant cultivator, as shown and described.

DESCRIPTION

FIG. 1 is an upper front perspective view of the main body for indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof;

FIG. 9 is a front perspective view that one of the shelves has been slid forward; and,

FIG. 10 is a front perspective view showing the state of use that the pod with planted plants is being installed at the shelf to cultivate.

The broken lines depict portions of the main body for indoor plant cultivator that form no part of the claimed design. The dash-dot broken lines define the boundary of the claimed design and form no part thereof. The portions of FIG. 10 drawn in broken lines show environmental structure only and form no part of the claimed design.
